TAP FIXTURE

Clifford E. Miller, St. Louis, Mo.

Application September 8, 1944, Serial No. 553,206

5 Claims. (Cl. 51—225)

The present invention relates to new and useful improvements in tap fixtures or appliances, and has for its primary object to provide, in a manner as hereinafter set forth, a device of this character comprising a unique construction and arrangement whereby the accurate sharpening and backing-off of the thread lead of tools of this character will be greatly expedited and simplified.

Another very important object of the invention is to provide a tap thread lead sharpening and backing-off fixture of the aforementioned character which is adapted to be readily adjusted to accommodate different sizes of tap flutes.

Still another very important object of the invention is to provide a fixture of the character described comprising novel adjusting means whereby the required back-off on the tap thread lead may be readily had.

Other objects of the invention are to provide a tap lead sharpening and backing-off fixture which will be comparatively simple in construction, strong, durable, highly efficient and reliable in use, compact and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a view showing a fixture constructed in accordance with the present invention in use on one end of a tap.

Figure 2 is a view in longitudinal section through the device.

Figure 3 is an elevational view, looking at the outer end of the device.

Figure 4 is a perspective view of the fixture, showing the parts separated.

Figure 5 is an elevational view, looking at the inner end of the fixture.

Referring now to the drawings in detail, it will be seen that reference character 1 designates generally a conventional tap, the thread lead 2 of which is to be sharpened and backed off. Toward this end, the tap 1 is mounted for oscillation between the usual centers 3 and 4 of a grinder and the thread lead 2 engaged with a grinding wheel 5.

The fixture constituting the present invention comprises a cylindrical metallic body 6 of suitable dimensions which is mounted on one end of the tap 1 and which receives the center 4. Toward this end, the body 6 includes an externally re-

duced forward end portion 7 having a circumferential groove or channel 8 therein. A ring 9 is mounted for rotary adjustment on the end portion 7 of the body 6. A set screw 10 is threadedly mounted in the ring 9 and engaged in the groove or channel 8 for securing said ring in adjusted position. Projecting forwardly from the ring 9 is a lug 11. An arcuate plate 12 is mounted for circumferential adjustment on the ring 9. Toward this end, the plate 12 has formed therein a slot 13 which accommodates a securing screw 14. Formed integrally with one end portion of the plate 12 is a lug 15. The lugs 11 and 15 are engageable in a pair of the flutes 16 of the tap 1 for securing the body 6 in the correct position thereon. This is shown to advantage in Figure 1 of the drawings.

The body 6 has formed in its forward end portion a concentric socket 17. A center point 18 is slidably mounted in the socket 17. A coil spring 19 yieldingly urges the center point 18 outwardly in the socket 17. The center point 18 comprises a flat upper portion 20 providing a shoulder 21. The portion 20 of the center point 18 accommodates a pin 22 which is mounted in an opening 23 provided therefor in the forward end portion 7 of the body 6. The shoulder 21 is engageable with the pin 22 for limiting outward movement of the center point 18 under the influence of the coil spring 19. The center point 18 is engageable in the usual center hole of the tap 1.

Mounted for rotary adjustment in the rear end portion of the body 6 is an eccentric center 24. The center 24 includes a metallic disc 25 having therein an off-center hole or socket 26 for the reception of the grinder center 4. The disc 25 is mounted for rotary adjustment in an off-center socket 27 which is provided therefor in the rear end portion of the body 6. Screws 28 are threadedly mounted in the rear end portion of the body 6 and the heads thereof are engaged with the disc 25 for securing said disc in adjusted position. A groove or kerf 29 in the disc 25 accommodates a screw driver or other suitable tool for rotatably adjusting said disc after the screws 28 have been loosened.

It is thought that the manner in which the device is used will be readily apparent from a consideration of the foregoing. Briefly, the body 6 is mounted on one end of the tap 1 in abutting engagement therewith. The center pin 18 is engaged in the usual center in the tap 1 by the coil spring 19. Being spring-pressed, the point 18 automatically adjusts itself to any size of center 50 in the tap. The device is secured in the correct

position on the tap 1 through the medium of the adjustable ring 9 with the lug 11 thereon and the coating lug 15 on the adjustable plate 12. The disc 25 is rotatably adjusted as may be necessary to get the correct center for the required backing off after the grinder center 4 has been engaged therein at 26. The thread lead 2 is then engaged with the grinding wheel 5 and the tap 1 is oscillated in any suitable manner to accomplish the sharpening and backing off of 10 said thread lead.

It is believed that the many advantages of a fixture constructed in accordance with the present invention will be readily understood, and although preferred embodiments of the device are as illustrated and described, it is to be understood that changes in the details of construction and in the combination and arrangement of parts may be resorted to which will fall within the scope of the invention as claimed.

What is claimed is:

1. A tap thread lead sharpening and backing-off fixture of the character described comprising a substantially cylindrical body, a center point yieldingly mounted in one end portion of said body and engageable in the center in one end of a tap, means for connecting said body to said one end of the tap for rotation therewith, and a rotatably adjustable disc mounted on the other end portion of the body and having a socket 30 therein for the reception of a supporting center.

2. A tap thread lead sharpening and backing-off fixture of the character described comprising a substantially cylindrical body engageable with one end of a tap, means for connecting said body to the tap for rotation therewith, said body having an off-center socket in its other end portion, a disc mounted for rotary adjustment in the socket, said disc having an off-center socket 35 therein for the reception of a supporting center, and screws threadedly mounted in the body and including heads engaged with the disc for securing said disc in adjusted position.

3. A tap thread lead sharpening and backing-off fixture of the character described comprising a substantially cylindrical body engageable with one end of a tap, a ring mounted for rotary ad-

justment on one end portion of said body, means for securing said ring in adjusted position, a lug projecting from the ring, a lug mounted for adjustment on the ring, said lugs being engageable in the flutes of the tap and cooperable with each other for securing the body to the tap for rotation therewith, and a rotatably adjustable center on the other end portion of the body for receiving a supporting center.

4. A tap thread lead sharpening and backing-off fixture of the character described comprising a substantially cylindrical body engageable with one end of a tap, said body having a concentric socket in one end portion and an off-center socket 15 in its other end portion, a spring-pressed center point slidably mounted in the first-named socket and engageable in the center of the tap, means for connecting the body to the tap for rotation therewith, a disc mounted for rotary adjustment in the second-named socket, said disc having an off-center socket therein for the reception of a supporting center, and means for securing the disc in adjusted position.

5. A tap thread lead sharpening and backing-off fixture of the character described comprising a substantially cylindrical body engageable with one end of a tap, said body including an externally reduced end portion having a concentric socket therein, a ring mounted for rotary adjustment on the reduced end portion of the body, means for securing said ring in adjusted position, a lug projecting from the ring, a plate adjustably mounted on the ring, a lug on said plate, the first and second-named lugs being engageable in flutes of the tap and cooperable for securing the body to said tap for rotation therewith, a center point slidably mounted in the socket and engageable in the center of the tap, a spring mounted in the socket and engaged with the center point for yieldingly urging same outwardly, the body having an off-center socket in its other end portion, a disc mounted for rotary adjustment in the second-named socket, said disc having an off-center socket therein for the reception 40 of a supporting center, and means for securing the disc in adjusted position.

CLIFFORD E. MILLER.
